AIRPLANE RUNNING LIGHT LAMP

Warren G. Grimes, Urbana, Ohio

Application April 29, 1939, Serial No. 270,893

2 Claims. (Cl. 176—34)

This invention relates to an airplane running or position light lamp and a method of focusing the beam light thereof.

The further object of this invention is to provide a more efficient airplane running light of extremely small size whereby the light will be much more effective than the minimum requirements and at the same time far smaller and hence cause less aero dynamic resistance than the present conventional types of running lights.

The further object of this invention is to provide a lamp for an airplane running light, which lamp is so specially shaped and has a reflector formed thereon whereby the light beams will be cut off from undesired directions and intensified in desired directions so as to provide a light having a candle power far above the minimum requirements even after the light has passed through the red or green colored window.

A still further object of this invention is to provide a running light lamp which has its beam light from the filament pre-focused with relation to a standard socket in which it is placed. Each lamp will in accordance to this invention always throw the beams of light of the desired intensity in the same direction when placed in the same type socket.

The further object of this invention is to provide a means of pre-focusing the beam light in relation to the socket and then fixing one part of the base by securing means to the lamp which securing means will cooperate with the standard socket in the proper placement of the lamp in the socket and make improper placement impossible.

With the foregoing and other objects in view as will hereinafter become apparent, this invention comprises the combinations of construction and arrangement of parts hereinafter claimed, set forth, and illustrated in the accompanying drawing, wherein:

Figure 1 is an exploded perspective view of the running light of this invention.

Figure 2 is a side elevational view, partly in section, of the running light.

Figure 3 is an elevational view partly in section of the improved lamp of this invention.

Figure 4 is a sectional view on line 4—4 of Figure 3.

Figure 5 is a side elevational view of the securing shell.

Figure 6 is an end elevation of Figure 5, and

Figure 7 is a perspective view of the securing collar or ring to be mounted on the lamp.

There is shown at 10 the running light of this

invention. The running light 10 includes a housing base 11. The housing base 11 consists of a counter-bored cylinder 12 from which extends a bowl 14 terminating in a somewhat elliptical flange 15. The flange 15 is provided with a circular recess 16 and a plurality of slots 17 to receive the base 18 and extending prongs 19 of a lens-covering dome 20, of transparent, colored material (glass or glass substitute) usually colored either red or green according to its location on the airplane in accordance with regulations. A dome-securing shield 21 has a spherical section 22 fitting snugly over a portion of the dome 20 to hold it securely in position. The shield 21 is itself held securely on the flange 15 by suitable machine screws placed thru openings 23 in the shield and screwed into threaded apertures 24 and the bowl flange 15, a depending flange 25 on shield 21 extending over the outside of the bowl flange 15.

Suitably and immovably secured within the counterbored cylinder 12 is the lamp-securing shell 26 having one end threaded as at 27 to receive a knurled cap nut 28 thereover, which nut supports the spring 30 against an insulation ring 31. The insulation ring 31 has the bared end of a conductor 32 soldered therein to form a terminal 33. The conductor 32 extends thru the center of the cap nut 28, 30 and the axial center of the coiled spring 30. The unthreaded end of the securing sleeve 26 has an enlarged head 34 which is provided with three unequally spaced bayonet slots 35.

The lamp 36 of this invention includes a lamp base 37 forming one contact and provided with a single contact 38 extending concentrically thereof, these contacts being connected to the filament 40 within the lamp 36 in the customary manner.

The lamp bulb 41 is not completely spherical in shape as is customary, but instead consists of one approximately spherical section 42 and a somewhat flattened section of a sphere of larger radius 43, the section 43 having a radius much greater than the spherical section 42. Section 43 and the lower or basal half 44 of spherical section 42 are silvered as at 45 so as to reflect all light striking the same thru the unsilvered or clear portion 46. Sections 42 and 43 are so chosen that the light is emitted from the lamp 42 only in the directions called for by existing standard aircraft requirements concerning running lights and may be changed if and when the requirements are changed, the light in all other directions being cut off and reflected so as to intensify the light in the desired direction.

The interior volume of the lamp bulb 41 which may be evacuated or filled with inert gas is substantially equal to that of a conventional bulb having the same size filament 40 whereby there is sufficient volume for absorbing and conducting the heat produced thereby. At the same time however, the reflecting surface on the section 43 is brought quite close to the filament 40 thereby enabling a much greater amount of light to be projected by this lamp 36 than is possible with a conventional lamp of the same volume and filament and having conventional reflectors placed outside the conventional spherical shaped lamp bulb.

The conventional running light emits 8 to 15 foot candles of light, but the minimum requirements by the Bureau of Air Commerce Regulations may be raised to require a greater light intensity visible through the colored dome. To comply with such regulations, it will be necessary 20 to increase the size of the conventional running light thus increasing the weight and the aerodynamic resistance thereof. The lamp of the present invention has been found by actual test to emit more than 75 foot candles of light as viewed thru the colored dome 20, and far from being larger in size than the regulation running light is in fact much smaller as it is substantially one quarter in over-all size in comparison to the conventional running light, therefore producing a 30 much more intense light with less space and less aerodynamic resistance.

The lamp 36 of this invention is mounted in the socket shell 26 by means of a securing collar 46 having an internal diameter slightly larger than the external diameter of the lamp base 37. This securing collar 46 is provided with a plurality of bayonet prongs 47 spaced thereabout at the same angle as the bayonet slots 35 so that the lamp 36 with the securing collar 46 thereon can be 40 secured to the socket shell 26 only in one position in relation thereto.

To insure that this position will be such that the maximum of light is emitted in the proper direction, the beam light from the lamp 36 is prefocused according to the following method:

The lamp is lighted and the beam emitted therefrom is focused so that it will project the maximum intensity of light in the desired direction relative to master socket similar to the socket 50

shell 26, the ring 46 being in position in the bayonet slots 35 but as yet unconnected to the lamp base 37. When the lamp has the desired beam light properly focused, the securing collar 46 and lamp base 37 are secured together by a suitable solder about the edges and in between the collar 46 and the lamp base 37, so that the lamp 36 is then in a position to emit its most intense beam light in proper relation to the ring 46. As the result thereof, when one lamp burns out and is replaced by another made according to this same method it is certain that the new lamp will emit its beam light in the same direction and same intensity as the original lamp irrespective of any slight inaccuracies between the position of the filament 40 and the silvered reflecting surface 45.

The novel features and the operation of this device will be apparent from the foregoing description. While the device has been shown in detail, it is obvious that this invention is not to be considered limited to the exact form disclosed, and that changes may be made therein within the scope of which is claimed, without departing from the spirit of the invention.

Having thus set forth and described the invention, what is claimed is:

1. A lamp comprising a lamp base, a light filament, and a lamp bulb, said lamp bulb consisting of two concave sections of different radii, the section of larger radius being somewhat flattened and located closer to the lamp filament, the section of smaller radius being substantially spherical, a reflecting surface completely covering said section of larger radius and a reflecting surface on only a portion of the basal half of the small spherical section.

2. A lamp comprising a lamp base, a light filament, and a lamp bulb, said lamp bulb consisting of two concave sections of different radii, the section of larger radius being somewhat flattened and located closer to the lamp filament, the section of smaller radius being substantially spherical, reflecting surface completely covering said flattened section of larger radius, a reflecting surface on only a portion of the basal half of the small spherical section and a clear window portion on the remainder to allow light beams to project in a desired direction only.
